UNITED STATES PATENT OFFICE.

STILLMAN W. ROBINSON AND HENRY J. DETMERS, OF COLUMBUS, OHIO.

DESIGN FOR A HYPODERMIC-SYRINGE BODY.

SPECIFICATION forming part of Design No. 28,344, dated March 8, 1898.

Application filed December 31, 1897. Serial No. 665,237. Term of patent 14 years.

To all whom it may concern:

Be it known that we, STILLMAN W. ROBINSON and HENRY J. DETMERS, residing at Columbus, in the county of Franklin and State 5 of Ohio, have invented and produced a new and original Design for a Body for Hypodermic Syringes, of which the following is a specification, reference being had to the accompanying drawings, forming part thereof.

10 Figure 1 is a view in side elevation of a hypodermic-syringe body, showing our new design. Fig. 2 is a central longitudinal section thereof.

As shown in the drawings, the leading or 15 material features of our design consist in the shape or pattern of the body or barrel a , having a perfectly smooth exterior, excepting at its rear end, where it terminates in an outwardly-projecting flange a' , concave on its 20 front face, and the rear face thereof lying in a plane at right angles to the longitudinal

axis of the barrel, the bore of the barrel being uniform and continuous to its extreme rear end a^2 . We also make said bore slightly flaring at a^3 . 25

We claim—

The design for the body of a hypodermic syringe, substantially as shown and described.

In testimony whereof we have signed our names to this specification in the presence of 30 the subscribing witnesses.

STILLMAN W. ROBINSON.
H. J. DETMERS.

Witnesses as to signature of Stillman W. Robinson:

ANNA C. FALL,
GEO. H. FALL,
HENRY C. GOODWIN.

Witnesses as to signature of H. J. Detmers:

CLARA L. OLNHAUSEN,
H. M. LYMAN.
